Des. 236,547
Patented Aug. 26, 1975

236,547

CABINET FOR A LINE PRINTER

Richard G. Clayton, Detroit, and Jerry J. Sims, Southfield, Mich., assignors to Burroughs Corporation, Detroit, Mich.

Filed Aug. 13, 1973, Ser. No. 387,682

Term of patent 14 years

Int. Cl. D18—02

U.S. Cl. D64—11 R

FIG. 1

FIG. 2

FIG. 1 is a front perspective view of a cabinet for a line printer showing our new design; and
FIG. 2 is a rear perspective view thereof.

We claim:

The ornamental design for a cabinet for a line printer, substantially as shown and described.
